(57) **CLAIM**

We claim the ornamental design for an aerosol can body, as shown and described.

DESCRIPTION

FIG. 1 is a front view of an aerosol can body, showing our new design;

FIG. 2 is a rear view thereof;

FIG. 3 is a top view thereof;

FIG. 4 is a bottom view thereof;

FIG. 5 is a left side view thereof;

FIG. 6 is a right side view thereof; and,

FIG. 7 is an enlarged section cut view taken along the line 7-7 in FIG. 1.

The even-length broken lines and unshaded areas within the broken lines depict portions of the aerosol can body that form no part of the claimed design. The dot-dash-dot broken lines define the bounds of the claim and form no part of the claimed design.
